UNITED STATES PATENT OFFICE.

THOMAS DONAHUE, OF BRANFORD, CONNECTICUT, ASSIGNOR TO THE
BRANFORD LOCK WORKS, OF SAME PLACE.

CYLINDER-LOCK.

SPECIFICATION forming part of Letters Patent No. 375,540, dated December 27, 1887.

Application filed September 5, 1887. Serial No. 218,798. (No model.)

To all whom it may concern:

Be it known that I, THOMAS DONAHUE, of Branford, in the county of New Haven and State of Connecticut, have invented a new Improvement in Cylinder-Locks; and I do hereby declare the following, when taken in connection with accompanying drawings and the letters of reference marked thereon, to be a full, clear, and exact description of the same, and which said drawings constitute part of this specification, and represent, in—

Figure 1, a partial section of a lock and door, showing the case inclosing the cylinder; Fig. 2, a perspective view of the case detached from the door; Fig. 3, a perspective view of the cylinder detached, also showing the plate for connecting the cylinder with the lock; Fig. 4, a side view of the cylinder, showing the recesses, the tumblers removed; Fig. 5, the key; Fig. 6, a central section through the cylinder and case in the plane of the key-hole, showing the tumblers in the position when the key is withdrawn; Fig. 7, an outer end view of the case and cylinder; Fig. 8, a transverse section through the cylinder in the plane of one of the tumblers; Fig. 9, one of the tumblers detached; Fig. 10, one block, *l*, detached; Fig. 11, same section as in Fig. 6, showing the tumblers drawn into the case as in the position for unlocking; Fig. 12, an end view of the cylinder, showing a flat key-hole.

This invention relates to an improvement in that class of cylinder-locks in which several radial tumblers are arranged, adapted to engage or disengage the surrounding case, the key being arranged to enter the lock in an axial direction, the edge of the key adapted to operate the said radial tumblers and cause them to engage or disengage the surrounding case accordingly as the key is withdrawn or introduced, the object of the invention being a cheap and simple construction and arrangement of the tumblers.

A represents the cylinder, shown detached in Figs. 3 and 4. This cylinder is adapted to set into a case, *B*, the said case being constructed to set into a recess formed in the face of the door, as seen in Fig. 1, and the case provided with a surrounding flange, *C*, at its outer end to lap onto the surface of the door. The

outer end of the cylinder *A* is exposed through an opening in the flange *C*, and in the cylinder in an axial plane the key-hole *a* is formed. The key-hole is flat, except at its center a bend is produced in the hole to give to the key-hole an irregular shape, the key itself being constructed with a corresponding longitudinal irregularity, *b*, as seen in Fig. 5. This insures the proper presentation of the key into the cylinder, and also serves to support the key in its central relation to the cylinder.

Transversely across the cylinder a series of recesses, *d*, are formed (see Fig. 4) in number corresponding to the number of tumblers required for the lock. These recesses are made from one side beyond the plane of the key-hole, as seen in Fig. 8, leaving the portion *e* of the cylinder beyond solid. The tumblers *f* (see Fig. 9) are cut from sheet metal in thickness corresponding to the respective recesses *d* in the cylinder, and in length correspond to the diameter of the cylinder. The width of the ends of the tumblers is such that when in place, as seen in Fig. 8, the ends of the tumblers stand in a central position in the cylinder. Each tumbler is constructed with an opening, *g*, through it in line with the key-hole, as seen in Figs. 8 and 9. The several tumblers are set into their respective recesses, and when so set into the key as it is introduced into the outer end of the cylinder will pass through the respective tumblers. The openings *g* are the same in length, but at varying distances from their respective ends. The key has its two edges constructed of reverse irregular shape, but so that the width of the key is substantially the same throughout and corresponds to the length of the openings *g* in the tumblers, and the irregularities in the edge of the key are such that when the key is inserted into the cylinder, as seen in Fig. 11, the tumblers will all be drawn entirely into the cylinder from both directions, so that at both ends they stand flush or within the surface of the cylinder, but when the key is withdrawn the irregular surfaces and the irregular lengths of the tumblers from the opening outward cause the tumblers to move diametrically in the cylinder, and so that the tumblers will enter corresponding recesses, *i*, formed in the surrounding casing *B*.

as seen in Fig. 6. The recesses *i* in the casing *B* are alike in opposite sides and are in position with relation to the cylinder, so that when the cylinder is in the locking position the tumblers will stand in line with the said recesses *i*, and so that they may be then forced therein as the key is withdrawn; but when the key is introduced the tumblers are drawn into the cylinder, and then as the cylinder with the tumblers is turned within the case *B* the tumblers are taken out of range of the openings *i*; hence they are held in that withdrawn position, and when so held within the case the key cannot be withdrawn. The recesses *i* are alike in opposite sides of the case *B*, so that the tumblers may work in either direction. This is necessary for the introduction of the key, because the tumblers will play to the right and left, according to the irregularities of the key, until the key is in place. Again, the recesses afford an advantage, because in any attempt to pick the lock, a tumbler, being withdrawn from one side by an instrument other than the key will almost unavoidably enter the recess in the opposite side.

To retain the tumblers in their proper position in the cylinder, so as to allow only diametrical movement, the recesses *d* outside the tumblers are filled by a block, *l*, (see Fig. 10,) introduced into the respective recesses, as seen in Fig. 8, and so that the said blocks form a guide for one side of the tumblers, while the bottom of the recess in the cylinder forms a guide for the opposite side. These blocks are held in place by the surrounding casing.

The cylinder is preferably introduced from the outer end of the case, and is therefore provided at its outer end with an annular flange, *m*, which sets into a corresponding recess in the face of the case. Then, to secure the cylinder in the case, a disk, *n*, is applied to the other end of the cylinder and secured thereto, as seen in Figs. 2 and 6, the disk extending over the inner end of the case.

Connection may be made between the cyl-

inder and the lock in any of the usual methods of making like connection between the cylinders of this class of the lock and the mechanism of the lock itself. As here represented, the inner end of the cylinder is constructed with a transverse groove, *o*, and into this groove a plate, *r*, is set, as seen in Fig. 6, the plate adapted to engage a corresponding groove, *t*, in the hub *u* of the latch or lock bolt.

I have represented and prefer to make the key-hole irregular in shape transversely, to indicate the proper position for the key; but the key may be flat, and the key-hole correspondingly flat, as indicated in Fig. 12.

It will be understood that the tumblers work with sufficient friction to retain them in their position in the cylinder without the aid of springs.

I claim—

The combination of the cylinder *A*, constructed with a key-hole in a longitudinal central plane, but of irregular shape in transverse section, the said cylinder constructed with recesses *d* from one side inward across the key-hole, tumblers *f* in length corresponding to the diameter of the cylinder and arranged in the respective recesses, the said tumblers being each constructed with an opening, *g*, through them in line with the key-hole, blocks *l*, in the respective recesses to form guides for one side of the tumblers, a case within which said cylinder is adapted to revolve, the said case constructed with recesses *i* diametrically opposite each other and corresponding to the respective tumblers, and a key transversely in irregular shape corresponding to the shape of the key-hole, and in width corresponding to the length of the opening *g* in the tumblers, the opposite edges of the key of reversely irregular shape, substantially as described.

THOMAS DONAHUE.
